UNITED STATES PATENT OFFICE

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

DOUBLE-CARPET WEAVE

Application filed May 24, 1924, Serial No. 715,699. Renewed December 14, 1929.

This invention relates to a carpet weave by which two carpets of the Wilton type may be woven simultaneously. In the weaving of such double carpet fabrics, as heretofore practiced, it has been found difficult to produce a satisfactory selvage as certain of the filling or weft threads have had a tendency to form loops or loose bends at the edges of the fabric.

It is the general object of my invention to provide a double carpet weave in which a close and firm selvage will be formed at each edge of the fabric. In the carrying out of this invention, I have shown my improved fabric as a three-shot Wilton weave and also as having a full set of pile warps in each portion of the fabric. The broad features of my invention, however, are not to be considered as limited to a weave of this exact construction, as many of the advantages may be utilized for instance in a two-shot weave, or in other similar constructions.

My invention further relates to certain arrangements and combinations of the component parts of a fabric as hereinafter described and more specifically set forth in the appended claims.

A preferred form of the invention is shown in the drawings in which

Figs. 1^a to 6^a inclusive, represent successive steps in the formation of the fabric at the selvage nearer the observer;

Figs. 1^b to 6^b inclusive, represent corresponding steps in the formation of the fabric at the more remote selvage, and

Fig. 7 is a diagrammatic perspective view showing the construction of my improved fabric.

Referring to the drawings, I have shown a double fabric comprising upper and lower portions each having a pair of binder warps B and B' and a plurality of pile warps W. Filling shots 10 to 19 inclusive are successively inserted in the upper fabric and corresponding shots 20 to 29 inclusive are successively inserted in the lower fabric. The different filling shots in the drawings are marked with plus and minus signs, the plus signs indicating that the filling so marked

is approaching the selvage nearer the observer and the minus signs indicating that the filling so marked extends in the opposite direction toward the more remote selvage.

In the drawings of the adjacent selvage, Figs. 1^a to 6^a, a loop of filling will consequently be formed around the edge of the fabric between each filling shot marked "plus" and the succeeding filling shot marked "minus". These loops of filling are indicated by full lines connecting the filling shots which thus form loops at the adjacent edge of the fabric. The loops around the more remote edge of the fabric will be between the shots marked "minus" and the succeeding shots marked "plus", and these loops around the remote edge are correspondingly marked by dotted lines in Figs. 1^b to 6^b inclusive.

For the purposes of this description, I have selected a set of pile warps P in the upper fabric portion and a corresponding set of pile warps marked P' in the lower fabric portion. In connecting these sets of pile warps P and P' to the jacquard cords or to the harnesses, I have separated the warps P and P' adjacent one selvage from the corresponding warps P and P' adjacent the opposite selvage and I have correspondingly separated each of the other sets of color or pile warps.

Having thus separated the warps P and P' between the selvages, I am able at a given point in the formation of the double fabric to call the warps P' from one fabric to form the pile adjacent one selvage and the warps P from the opposite fabric to form the pile adjacent the second selvage. By calling the warps in this manner, certain important advantages are attained, as will be hereinafter explained.

I so dispose the warps that the warp threads adjacent a given selvage will be called from that portion of the fabric in which a filling shot has just left the selvage. The warps P' in Fig. 1^a have thus been called from the lower fabric, immediately after the filling shot 23 has been inserted with the shuttle travelling toward the observer and the filling extending from the adjacent edge of the fabric. As the next filling shot 24 is

inserted and beaten up, it forms a loop at the selvage, drawn sharply over the bend of the warps P' and firmly binds the selvage as indicated by the line 23—24 in Fig. 2^a.

If, on the other hand, the warps P had been called at the point in the weave indicated in Fig. 1^a, there would have been a long stretch of pile warp P , which would have crossed the filling between the filling shot 23 and the filling shot 24 and closely adjacent the latter. When the fabric was beaten up, the long stretch of pile warp P would have caught and held the filling and would have caused it to be beaten up therewith. As the filling shot 24 is much nearer the filling shot 23 after beating up, this operation would produce surplus filling between the points 23 and 24, which surplus must necessarily form a loose bend or loop at the edge of the selvage. The formation of these loose bends or loops at the selvage is effectively avoided in my improved weave, as above described.

At the remote edge of the fabric, as indicated in Figs. 1^b to 6^b, the corresponding warps are called from the fabric in which a filling shot has just left the fabric at the remote edge thereof, the result being the same as previously described.

In Fig. 7 the general construction of the fabric is indicated in perspective, this view clearly indicating the separation of the warps into two separate groups so that they can be called from opposite portions of the fabric adjacent opposite selvages. By thus calling the pile warps adjacent each selvage from the fabric in which a filling shot has just left the selvage, the formation of loops in the filling adjacent the selvage is effectively prevented.

The phrase "each having a full set of pile warps therein" as used in the claims indicates that the upper fabric has a full and complete set of all of the kinds or colors of warps used to produce the double fabric and that the lower fabric has an identical but separate complete set of warps.

Having thus described my invention and the advantages thereof I do not wish to be limited to the details herein disclosed otherwise than as set forth in the claims, but what

I claim is:—

1. A double carpet weave comprising upper and lower fabrics each having a full set of pile warps therein, said pile warps being divided and the warps being called so that the pile warps which are raised adjacent a given selvage will be called from that fabric portion in which a pick of filling has just left the edge of the fabric and is about to form a loop at the selvage, and the pile warps which are raised adjacent the other selvage will be called from the opposite fabric.

2. A double carpet weave comprising upper and lower fabrics each having a full set of pile warps therein, said pile warps being

divided and the warps being called so that each pile warp in one fabric portion which is raised adjacent a given selvage passes through the opposite fabric portion between a filling thread in said opposite portion which has just entered said selvage and a succeeding filling thread that is about to leave said selvage. 70

3. A double fabric weave comprising upper and lower fabrics between which extend pile forming threads which are incorporated into both fabrics, said pile warps being divided and the warps being called so that the pile warps which are raised adjacent a given selvage will be called from that fabric portion in which a pick of filling has just left the edge of the fabric, and the pile warps which are raised adjacent the other selvage will be called from the other fabric. 75

4. A double fabric weave comprising upper and lower fabrics between which extend pile forming warp threads which are incorporated into each fabric, said pile warp threads being divided and the warps being called so that each pile warp in one fabric portion which is raised adjacent the given selvage passes through the opposite fabric portion between a filling thread in said opposite portion which has just entered said selvage and a succeeding filling thread that is about to leave said selvage. 80

5. A double fabric weave comprising upper and lower fabrics from each of which pile forming threads may be drawn and between which extend pile yarns which are incorporated into both fabrics, said pile yarns being divided into two groups transversely of the width of the fabrics, one of said groups being adjacent one selvage and extending upwardly and the other group being adjacent the other selvage and extending downwardly, a plurality of shots of filling to hold the pile forming threads in position, one of said shots of filling secured to the lower fabric and entering said fabric at one selvage, said shot of filling passing under all the threads of the upwardly extending group of warp threads adjacent the selvage which the shot of filling enters and over all the threads of the other group of pile yarns. 100

6. A double fabric weave comprising upper and lower fabrics from each of which pile forming threads may be drawn and between which extend pile yarns which are incorporated into both fabrics, said pile yarns being divided into two groups transversely of the width of the fabrics, one of said groups adjacent one selvage extending upwardly and the other group of pile yarns adjacent the other selvage extending downwardly, and a plurality of shots of filling to hold the pile forming threads in position, one of said shots of filling secured to one of the fabrics and entering said fabric and passing under all the threads of the group adjacent one selvage and 115

over all the threads of the other group adjacent the other selvage.

7. A double fabric weave comprising upper and lower fabrics from each of which pile forming threads may be drawn and between which extend pile threads which are incorporated into both fabrics, the pile forming threads being divided into two groups transversely of the fabrics, one group being adjacent one selvage and the other group being adjacent the other selvage, and a plurality of shots of filling to hold the pile forming threads in position, one of said shots of filling entering the lower fabric at one selvage and passing under the pile forming threads of the group adjacent the selvage which the shot of filling enters, and also passing over the pile forming threads of the group which is adjacent the other selvage.

20 In testimony whereof I have hereunto affixed my signature.

RICHARD GREENLEAF TURNER.
